PAPER FASTENER

Russell G. Bourdon, Muskegon, Mich., assignor to
The Shaw-Walker Company, Muskegon, Mich.,
a corporation of Michigan

Application June 14, 1940, Serial No. 340,416

6 Claims. (Cl. 24—153)

This invention relates to improvements in paper fasteners for use with backs or folders for filing or enclosing papers in succession and consists of the matters hereinafter described and more particularly pointed out in the appended claims.

The object of the invention is to provide a paper fastener of the kind which is of simple and economical construction and of ready and easy operation and which may be applied to a back or folder without a special punch or punch machine. Another object of the invention is to provide a fastener which is automatically positioned when it is applied to a folder.

The advantages of the invention will appear more fully as I proceed with my specification.

In the drawing:

Figure 1 is a perspective view showing a folder provided with one of the improved paper fasteners.

Figure 2 is a perspective view of the blank cut and formed to make the fastener.

Figures 3 and 4 are perspective views illustrating the steps of applying the fastener to the folder.

Figure 5 is a perspective view showing another way of applying the fastener to the folder.

Figures 6 and 7 show a modification of the fastener made in two parts, said parts as shown being in disassembled relation.

Figure 8 is a perspective view showing the part illustrated in Figure 7 as it appears when closed upon itself and looked at from the rear.

Figure 9 is a perspective view showing the parts illustrated in Figures 7 and 8 as when being applied to a folder.

Figure 10 is a view showing the part illustrated in Figures 7, 8 and 9 in place on the folder and the part illustrated in Figure 6 in position to be engaged with the first named part.

Figure 11 is a perspective view showing the paper fastener properly applied to the folder and ready for use.

Referring now to that embodiment of the invention shown in Figures 1 to 5, inclusive: The improved fastener comprises a base 15 and oppositely extending prongs 16, 16 disposed at right angles to said base. The base has a short extension 17 on one side of the aligned prongs 16, and a longer extension 18 on the other side thereof. The short extension 17 is offset somewhat from the plane of the base to provide a curved shoulder 19 which, as will appear later, is designed to engage a perforation in a folder to which the fastener is to be applied.

To strengthen the base 15, it is preferably embossed to provide laterally spaced ribs 20 extending along its lateral edges. The boss is continued across the base to provide a bottom rib 20a adjacent the curved shoulder 19. Beyond the ends of the rib 20 the base is bent at right angles to provide a preferably pointed wing 21. Said wing is curved about the aligned near edges 16a of the prongs 16.

10 The improved fastener is designed to be used with a folder provided with a perforation 22 spaced at the required distance from one edge of the folder. To apply the fastener to such folder, it is gripped by the finger and thumb, as shown 15 in dotted lines in Figure 3, and the wing 21 is inserted through the perforation 22, with the ribs 20 facing forward and the wing 21 directed towards the near edge of the folder. The base extension 18 is pushed through said perforation 20 until the edges 16a of the prongs 16 engage the 25 front face of the folder and is then swung forwardly to bring the curved shoulder 19 into engagement with the proximate edge of the perforation. This brings the rear face of the short 30 base extension 17 into contact with the front face of the folder, and the base extension 18 against the back of the folder, with the edge of the folder engaged in the angle between the wing 21 and the base extension 18 as shown in Figure 4. Said 35 wing is then bent down against the front face of the folder as shown in Figure 1. The fastener is then ready for use with papers provided with perforations like the perforation 22 in the usual manner.

35 Where the perforations in the folder are located differently and are not spaced from one edge of the folder to permit application of fastener as described above, it may be applied as follows: In Figure 5 is shown a folder with a 40 perforation located near one corner. In such case the base of the fastener is inserted through the perforation but with the wing 21 turned away from the near edge of the folder. Then the base extension 18 is swung about the near edges 16a 45 of the prongs 16 against the front face of the folder, with the curved shoulder 19 in engagement with the proximate edge of the perforation. In this movement, by pressure on the back of the base 18, the pointed prong will be caused to cut 50 a slit in the folder; and by reason of the curvature of the prong 21 about the said edges 16a as an axis, the base may be brought against the rear face of the folder without rupturing the slit cut by said wing. The wing 21 is then turned down 55 against the front face of the folder as before.

In the modification shown in Figures 6 to 11, inclusive, the prongs are made in one piece, and the base is made in a second piece. 25 indicates the prong member and 26 the base member. The base portion 26 is in approximately U-form, having a leg 26^a which is to engage the face of the folder, and a leg 26^b which is to engage the back of the folder. The leg 26^a is wide throughout the greater part of its length, but its edges are converged towards the bottom as indicated at 27. In the lower part of said leg is provided an elongated slot 28 extending parallel to its lateral edges. The leg portion 26^b is of the width of the leg portion 26^a at the top where it joins said last named leg, but its edges are sharply converged shortly below that point, where it is continued as a narrow tongue 29. Intermediate the length of said tongue it has a part offset from the main plane of the tongue to provide a U-shaped strap 30. Said strap is so located with reference to the slot 28 in the leg 26^a of the base that when the two parts of the base are brought together, the U-shaped strap 30 will project through the slot 28 to present a channel extending forwardly of the face of the leg 26^a, as shown in Figure 8.

The application of the two-piece fastener to a folder is illustrated in Figures 9, 10 and 11.

The folder is provided as before with a perforation 31 adjacent an edge 32. The U-shaped base in form as shown in Figure 8 is slipped upon the folder, with the leg 26^a on the front side thereof, and the leg 26^b on the back of the folder, and in line with the hole 31. The fastener is pushed towards the perforation 31 until the edge 32 is engaged by the head of the U-shaped base 26, as shown in Figure 10, whereupon the strap 30 is pushed through the slot 28. Then the prong member 25 is pushed endwise through the channel thus presented until the prongs of which it is comprised extend at like distances at either side of said strap. This completes the application of the paper fastener which is now ready for use in the usual way.

I claim as my invention:

1. A metal paper fastener adapted to be attached to a folder having a perforation at a distance from one edge of the folder, comprising an elongated base having back and front parts bendable at an angle for engagement with the back, edge and face of said folder, means offset from said base at a right angle to the plane thereof for locking it in said perforation, and narrow elongated prongs extending in line at each side of said base when the fastener is attached to said folder.

2. A metal paper fastener adapted to be attached to a folder, comprising an elongated base having oppositely extending prongs disposed at right angles to said base, said base having a short extension on one side of said prongs with a rearwardly offset curved shoulder and a longer extension on the other side having a wing extending forwardly at an angle to said base.

3. A metal paper fastener adapted to be attached to a folder, comprising an elongated base having laterally extending prongs disposed at right angles to said base, said base having a short extension on one side of said prongs with a rearwardly offset curved shoulder and a longer extension on the other side having a wing extending forwardly at right angles to the plane of said base, said wing being curved in an arc about the line of the near edges of said laterally extending prongs as an axis.

4. A metal paper fastener adapted to be attached to a folder having a perforation, comprising an elongated base having oppositely extending prongs disposed at right angles to said base, said base having a short extension on one side of said prongs with a rearwardly offset curved shoulder and a longer extension on the other side providing an end wing adapted to be bent back upon said base.

5. A metal paper fastener adapted to be attached to a folder having a perforation, comprising a U-shaped base having a wide slotted leg for engagement with the face of the folder and a narrower leg for engagement with the back of the folder, said narrower leg having an offset part to provide a U-shaped strap when pushed through the slot in said wider leg, and a prong member adapted to be engaged under said strap and lock said base legs together and to said folder.

6. A metal paper fastener adapted to be attached to a folder having a perforation, comprising a U-shaped base having a wide slotted leg for engagement with the face of the folder and a narrower leg for engagement with the back of the folder, with the proximate edge of the folder engaged by the top of the U, said narrower leg having a forwardly offset part to provide, when pushed through said perforation and the slot in said wider leg, a strap projecting forwardly of said wider leg, and a metal strip adapted to be engaged under said strap and lock said base legs together and to said folder, said strip being of a length to present prongs extending laterally at either side of said base.

RUSSELL G. BOURDON.
